INVENTOR,

Andrew Priquet,

By John Edward,
ATTORNEY.

UNITED STATES PATENT OFFICE.

ANDREW PRIQUET, OF HALEDON, NEW JERSEY, ASSIGNOR TO MIESCH MANUFACTURING COMPANY, OF PATERSON, NEW JERSEY, A CORPORATION OF NEW JERSEY.

LET-OFF MECHANISM FOR LOOMS.

1,290,346.

Specification of Letters Patent.

Patented Jan. 7, 1919.

Application filed April 25, 1918. Serial No. 230,669.

To all whom it may concern:

Be it known that I, ANDREW PRIQUET, a citizen of the United States, residing at Haledon, in the county of Passaic and State 5 of New Jersey, have invented certain new and useful Improvements in Let-Off Mechanisms for Looms, of which the following is a specification.

This invention relates to let-off mechanisms for looms and its principal object is to produce a simple and reliable let-off mechanism whose operation will be characterized by avoidance of the slightest jerky or vibratory release of the beam, 10 the release on the other hand being always of an even slip-friction character regardless of the degree of tension which, according to the goods being woven, it may be necessary to impose. Another object is to 15 provide for an ample letting back of the warp in such manner that while the slack that would otherwise be produced is taken up by an appropriate part of the mechanism another part thereof holds the beam securely 20 against rotation at this time. Still another object is to construct the mechanism so as to afford ample freedom of access in introducing the filled beams and removing the empty ones.

30 In the drawing,

Figure 1 is a side elevation of the improved let-off mechanism: and

Fig. 2 is a plan view the support for the mechanism being shown in section on the 35 line 2—2 in Fig. 1.

a designates suitable brackets forming the said support, and *b* a beam journaled therein on a horizontal axis and having peripherally grooved flanges, according to 40 a well-known construction.

c is a lever consisting of two lever arms *d* *d* fulcrumed on stud *e* in the brackets *a* and connected by the rods *f* and *g*, on the former of which is preferably journaled 45 a roller *h* to form the warp-guiding portion of lever *c* and on the latter of which may be arranged any suitable number of weights *i*; rod *g* is preferably outward of rod *f*, and rod *f* is preferably arranged in upstanding 50 portions *d'* of the lever arms *d*.

j is another lever consisting of two lever arms *k* *k* fulcrumed on studs *l* in the brackets *a* and connected by a rod *m*, on which is preferably journaled a roller *n* to 55 form the warp-guiding portion of lever *j*.

Inwardly of rod *m* holes are formed in the lever arms *k* to receive studs *o* of braking shoes *p*, which are thus pivoted in the lever arms and may be shifted therein parallel with the axis of the beam to suit various 60 widths of beams. The lever arms in this case have slight movement with reference to each other so that either brake device *p* can accommodate itself independently of the other to periphery-irregularities of the 65 beam. Each shoe *p* has a braking face *q* curved to the same arc as and in cross section more or less conforming to the grooved periphery of the beam. The braking shoes may, with advantage, be formed of yielding 70 rubber.

The arrangement is such that the roller *n* of lever *j* is between the beam and the roller *h*. The warp is adapted to extend from the beam, over roller *n* and then under 75 roller *h*, to the take-up mechanism.

Brake device *p* moves in an arc cutting the periphery of the beam at a point in substantially the same horizontal plane as the axis of the beam, with which it is noted it 80 has limited contact. Lever *j*, therefore, tends by its own weight plus the weight of lever *c* acting on lever *j* through the warp, to resist rotation of the beam, but without appreciable disposition of its brake device 85 to adhere thereto in a manner characteristic of the well-known bands or straps. In view of these circumstances, and in view of the further fact that according to my invention the lever *c* does not have contact with 90 lever *j* at any time in automatic letting off, but is simply raised by the warp to a position where the roller *h* is sufficiently high with respect to roller *n* so that the weight of lever *c* becomes more or less an immaterial factor in exerting downward pressure on the brake device, the release of the beam takes place in an entire absence of jerkiness and without the beam "jumping" 95 from one braked position to the next, which of course produces markings, such as "shiers" or undue spacings of the weft, in the finished fabric. The fluctuation of the pressure of the brake device on the beam I find operates to best advantage in causing 100 the release to be always of a slip-friction character, without jerkiness or jumping, if, as preferred, the element *q* is a resilient medium, as rubber. Of course, following 105 each release, the lever *c* tends to fall so that 110

its weight again becomes effective to exert pressure on the brake device *p*; but the letting off action is so under control at all times that the movement of either lever is 5 hardly apparent.

In letting-back the warp, the member *c* retains the warp under control (in a state of tension) and the member *j* holds the beam fast, until the member *c* engages some obstacle below, as the floor; preferably member *c* is so arranged and constructed as to give it ample range of free downward movement without the tension under which the members thus maintain the warp being 10 affected.

After a letting back of the warp the automatic release of the latter will obviously begin when member *c* has been raised to about the position shown, the beam up to that 15 point being held fast.

When member *c* is allowed to fall to the floor and member *j* raised as far as it will go, ample clearance is afforded for the operations incident to the replacing of an empty 20 beam by a filled one.

Copies of this patent may be obtained for five cents each, by addressing the "Commissioner of Patents, Washington, D. C."

Having thus fully described my invention, what I claim as new and desire to secure by Letters Patent is:—

In combination, a support, a warp-beam journaled in the support, a warp-tension means arranged in the support and including two warp-tension levers each having a warp-guiding portion arranged outwardly of the periphery of the beam, one lever having its fulcrum above the horizontal axis of the beam and including a brake device movable with said lever in an arc cutting the periphery of the beam and normally having limited contact with said periphery at a point near the same horizontal plane as said axis and said lever having its warp-guiding portion nearer to the beam than the warp-guiding portion of the other lever, and said other lever being movable upwardly to the warp-releasing limit clear of the first-named lever, the warp being adapted to extend over and under, respectively, the warp guiding portions of the first and second levers.

In testimony whereof I affix my signature.

ANDREW PRIQUET.
